UNITED STATES PATENT OFFICE.

JOHN SCHUMACHER, OF LOS ANGELES, CALIFORNIA.

COVERED-EDGE PLASTER BOARD.

Application filed November 4, 1924. Serial No. 747,794.

This invention relates to plaster board, plaster lath, and the like, comprising a cementitious core and covering sheets of pliable material, such as paper. Such board or lath in the process of manufacture, transportation of the finished board, and installation of the same, is subject to injury and damage at the edges. It has been proposed to protect the edges with a covering of pliable material which may be accomplished by folding over a marginal edge portion of a covering sheet or by applying a separate strip thereto. To effectively protect the edge with such a covering, the latter should be bound thereto. In the installation of board or lath of this character, it is often found advantageous to fill the joints with a plaster cement or like binder. Such joint material does not adhere as effectively to the paper as to the plaster body.

The primary object of this invention is to provide a plaster board having a margin of a covering sheet folded over at the edge so as to reinforce and protect the latter, the folded portion at the edge being such as to dispose sufficient of the plaster body to provide binding areas.

These objects together with other objects and corresponding accomplishments are obtained by means of the embodiments of my invention illustrated in the accompanying drawing, in which:

Fig. 1 is a perspective view showing a fragment of a plaster board constructed in accordance with my invention; Fig. 2 is a perspective view showing a fragment of a board illustrating another form of the invention; and Fig. 3 is a perspective view of a fragment of the board showing still another form of the invention.

Referring more particularly to Fig. 1, a plaster body 5 has covering sheets 6 and 7 of paper bound thereto by means now well known in the art. The edges of the sheets 6 are scalloped as indicated by 8. The scallops are of such dimensions that when folded over the edge of the board, they will extend only partially across the body of the plaster. The covering sheet 7 is of the same character as sheet 6 and is provided with scallops 9. These scallops are of such configuration that areas of the plaster body are exposed. Plaster cement applied between the edges of adjoining plaster board will contact with the plaster and adhere firmly in position, thereby providing a good joint.

In Fig. 2, a plaster body 10 is shown covered by sheets 11 and 12. The edges of the sheets are serrated, teeth being formed which are herein shown as extending nearer the opposite side of the board than the scallops in Fig. 1. These teeth indicated by 13 and 14 are preferably arranged to mesh so that there is a wavy band of exposed plaster at the edge to which the joint cement plaster may adhere.

Instead of the construction shown in Fig. 2, only one of the sheets may have serrated edges. Such a construction is shown in Fig. 3, the plaster core being indicated by 15, a covering sheet of the usual form being indicated by 16, and a serrated edge sheet being indicated by 17. The teeth 18 may be extended close to the sheet 16. This construction leaves exposed areas of plaster to which the plaster cement may adhere.

It is obvious that various other constructions may be employed, that is, the serrations or scallops may be of various configurations. In the claims appended hereto the terms serrations or scallops are used broadly without regard to the special configurations.

What I claim is:

1. A plaster board of the character described comprising a cementitious body and a covering sheet disposed on the face thereof, said covering sheet having a serrated edge folded over the edge of said body so as to expose areas of the latter at the edges.

2. A plaster board of the character described comprising a cementitious body and a covering sheet disposed on each face thereof, one of said covering sheets having serrated edges folded over the edge of the body so as to expose areas of the latter at the edges.

3. A plaster board of the character described comprising a body and a covering sheet disposed on each face thereof, said covering sheet having a serrated edge folded over the edge of said body so as to expose areas of the latter at the edge.

4. A plaster board of the character described comprising a body and a covering sheet disposed on each face thereof, said covering sheets having opposite edges serrated and folded over the edges of said body, said serrations being so disposed as to expose areas of the body at the edges.

5. A plaster board comprising, in combination, a body of plaster or the like, cover

- 2
- sheets covering the opposite faces of said body and adhering thereto, the margins of said sheets being folded to cover the edges of said body without overlapping; said margins being deformed at intervals lengthwise thereof to supply anchorage with the material of said body, the underformed portions of said margins conforming to the edges of said body.
- 10 6. A plaster board comprising, in combination, a body of plaster or the like, cover sheets covering the opposite faces of said body and adhering thereto, the margins of said sheets being folded to cover the edges of said body without overlapping; said margins being cut out at intervals lengthwise thereof to supply anchorage with the material of said body, the uncut portions of said margins conforming to the edges of said body.
- 15 7. A plaster board comprising, in combination, a body of plaster or the like, cover sheets covering the opposite faces of said body and adhering thereto, the margins of said sheets being folded to cover the edges of said body without overlapping, said margins being notched at intervals lengthwise thereof to supply anchorage with the material of said body.
- 20 8. A plaster board comprising, in combination, a body of plaster or the like, cover sheets covering the opposite faces of said body and adhering thereto to reinforce said body from edge to edge, the margins of said cover sheets being serrated and folded to cover the edges of said body, the serrations of said margins serving to form a mechanical bond with the body.
- 25 9. A plaster board comprising a body, cover sheets applied to the faces of said body and having marginal portions folded over and upon the edge of said body, said marginal portions being serrated along their edges.
- 10 10. A plaster board comprising a plaster body, sheets of fibrous material on opposite sides of said body, the margins of one of said sheets being folded over upon an edge face of said body and provided along its edge with serrations.
- 30 11. A plaster board comprising a plaster body, sheets of fibrous material on opposite sides of said body, the margins of said sheets being folded over an edge of said body and terminating in spaced relation, there being formed longitudinally spaced serrations throughout said folded portions.
- 35 12. A plaster board comprising a plaster body and sheets of fibrous material covering the faces thereof, the marginal portions of said sheets being folded over and embedded in the edge face of said body and terminating in spaced relation substantially midway of said edge face, said marginal portions being serrated to provide a bond with the material of said body.

In witness that I claim the foregoing I have hereunto subscribed my name this 27th day of October, 1924.

JOHN SCHUMACHER.
